United States Patent Office.

GEORGE HOWELL, OF BALTIMORE, MARYLAND.

Letters Patent No. 98,869, dated January 18, 1870.

IMPROVED READING AND WRITING-STAND.

The Schedule referred to in these Letters Patent and making part of the same.

To all whom it may concern:

Be it known that I, GEORGE HOWELL, of the city of Baltimore, State of Maryland, have invented a new and useful Combination Reading and Writing-Stand, of which I declare the following specification to be a true description, reference being had to the accompanying drawings, which form a part thereof.

The nature of my invention consists in the peculiar construction and operation of a convertible article of furniture, composed of a number of parts easily and simply adjusted for use when attached to a chair, table, bedstead, or other convenient stand, as a combined book-stand and writing-desk, or as a book-stand or music-stand only, and readily convertible from the one to the other, the whole apparatus being simple and durable in construction, and so compact as to be contained in the small portable wooden box, which may be used as a base for the music or reading-stand, and is so constructed that it serves to form the writing-stand, all as hereinafter more fully described.

In the drawings, the same letter of reference indicates corresponding parts.

Figure 1 is a section of my combination reading and writing-stand, through the centre of the various parts.

Figure 2 is a front view of the same.

Figure 3 is a front view of my invention as a reading or music-stand.

Figure 4 is a perspective view of the portable box.

Figure 5 is a slotted arm, having a slide, *i*, and *q* is a section of the same, through the line *g g*.

A is a hollow standard, whose lower end is solid, and threaded, the upper end being open, and finished off with any desired ornamentation.

Near the upper end is a set-screw, *s*.

Within the standard *A*, working easily and smoothly, is a cylindrical rod, *B*, the lower end of which is cut off squarely, while the upper end is threaded.

Screwed down upon this threaded end, for the purposes hereinafter set forth, is a slotted arm, *F*, (figs. 1 and 2,) the width of the slot being the diameter of rod *B*.

On top of this arm, and supported by it, is the writing-table *R D D'*, formed of the box *R*, which box I will now describe.

Fig. 4 is a view of this box alone. The top *D*, side *D'*, and bottom of the box, are hinged together, so that, when open fully, their surfaces are in the same plane, as shown in fig. 1, and when folded up, they completely close the box. To fasten the box close, a hook and eye, or any other means may be used. The other sides and bottom of the box are secured together in the ordinary way.

In the bottom of the box is cut a slot, *Q*.

When the box *R* is placed upon arm *F*, slot *Q* corresponds with the slot in the arm.

Through these slots a bolt, *b*, is inserted, upon which

threaded coupling *K* is screwed, which clamps together the box and arm.

In the top of coupling *K* is screwed rod *E*, the office of which is to serve as a support for the adjustable reading (or book) stand.

The upper end of rod *E* has an ornamented nut-head *z*.

Working easily upon rod *E*, and adjusted by set-screw *s'*, is a slide, *L*, to which is attached the top piece *P* of the book-stand.

At each end of top piece *P*, from the top, is formed a recess, into which fits a brass tongue attached to the back of arms *m* and *m'*, shown by dotted lines in fig. 1.

These arms are pivoted to slat *o*, and are each provided with a recess to receive the ends of slat *h*, which is removable.

Slat *o* has a hinged ledge, *l*, provided with tines *ee*, for supporting and holding open the book.

The reading-stand being so constructed, it is plain that it can be readily taken apart, folded, and compactly laid away in the box.

To the lower end of standard *A* is represented, screwed, a base, *G*, in which is cut a slot, *S*, to receive one of the jaws of the clamp *C C'*.

The base rests upon the chair or table *W*, and is firmly secured thereto by the clamp.

This clamp is an important feature of my invention. It is composed of the two pieces *C C'*, and the set-screw *s*. It may be made of brass, or other metal. Its upper jaw, *C*, has a solid screw-arm, which works in the hollow threaded arm of the jaw *C'*. The upper jaw and arm are of one casting, as are the lower jaw and arm. The clamp is very simple in construction, and is obviously adaptable to any thickness of chair-seat or table. It is better fitted to serve the purpose intended than would be a clamp made after the "monkey-wrench" device, in that the jaw *C* is not necessarily in the line of the jaw *C'*, and, consequently, when, by reason of the conformation of the furniture to which my stand is attached, it is not possible or convenient to adjust the jaw *C* directly under the jaw *C'*, it can be moved to the one side or the other, and the stand still be securely clamped.

Instead of using base *G*, the screw-end of standard *A* may be inserted in the screw-hole *v* of the slotted arm *H*, fig. 5, and the arm be used as hereinafter described. This arm is provided with a slide, *i*, running in side grooves in the slot, as shown in section *g*. Its object is to afford a means of adjusting the stand at a greater or lesser distance from the chair.

The standard *A* being screwed in hole *v*, the arm *H* is rested upon the furniture *W*, and the jaw *C* upon slide *i*. The arm having a limited longitudinal movement independent of the slide, the standard can be adjusted to any convenient distance from the person using it, within the limit of the slot's length.

By removing arm *F*, with desk *D D'*, and connect-

ing rods B and E, by coupling K, my invention becomes simply a book or music-stand, which can be attached to chair, table, bedstead, or box, R, or to any convenient special stand.

The angle of the book or music-stand can be rendered adjustable by reaming the hole in slide L, and supporting the angle by an adjustable rest, X, sliding on rod E.

Rod B can be made hollow, and provided with a rod working in it, whose relation corresponds to that of rod B with standard A, and the stand be thus rendered capable of greater adjustable elevation.

The various parts of my reading and writing-stand are so separable as to be easily and conveniently packed in the portable rectangular wooden box R, hereinbefore described, which forms a part of my invention. This box, stood on end, with hinged sides partly open, and standard attached through hole u, in the other end, forms a steady and convenient base for the reading or music-stand.

For convenience in adjusting, I make the various screws used in my apparatus, except set-screws, of the same thread and diameter.

I claim, as my invention—

1. The box R, constructed substantially as described,

having its top D, side D', and bottom hinged together, and its bottom slotted, for the purposes set forth.

2. An adjustable convertible combination reading and writing-stand, consisting of clamp C C', arm H, standard A, rod B, arm F, box R, bolt b, rod E, and reading-stand L p m m' h o, substantially as and for the purpose set forth.

3. The reading-stand, composed of the adjustable slide L, top piece P, slats o and h, arms m m', rod E, and adjustable rest x, when constructed and arranged as and for the purpose set forth.

4. The combination and arrangement of the reading-stand and rod E, with coupling K, rod B, standard A, and base G, as described.

5. The combination and arrangement of the reading-desk, rod E, coupling k, and bolt b, with desk R D D', arm F, rod B, standard A, base G, and clamp C C', substantially as and for the purpose set forth.

The above specification of my invention signed and witnessed, at Washington, D. C., this 23d day of October, 1869.

GEORGE HOWELL.
